SASH OPERATOR AND FASTENER

Chester O. Goserud, St. Paul, Minn.

Application November 18, 1932, Serial No. 643,158

17 Claims. (Cl. 20—55)

My invention relates to sash operators and fasteners and particularly to devices in which a swinging storm sash is moved into opening position upon movement of one of the sliding sash of a double hung window such as shown in my copending application for patent, Serial Number 501,764.

An object of the invention resides in providing a device by means of which the sliding sash may be more fully opened than would be possible with a sash equipped with a device such as disclosed in the above noted application for patent.

Another object of the invention resides in providing a sash operator by means of which the sliding sash may have appreciable movement after the storm sash reaches its fully open position.

A still further object of the invention resides in providing a device for swinging the storm sash and in further providing jointed links connected to the sliding sash and to said device for operating the same.

A feature of the invention resides in constructing said sash device with a pair of jointed arms, one pivoted to the frame of the sash and the other to the storm sash and in further employing a lever movable with the arm pivoted to the frame and in pivoting one of said links to said lever.

An object of the invention resides in arranging the links so that the same jack knife after the storm sash has been partially opened to permit of the further opening of the sliding sash.

Other objects of the invention reside in the novel combination and arrangement of parts and in the details of construction hereinafter illustrated and/or described.

In the drawings:

Fig. 1 is a perspective view of a window illustrating an embodiment of my invention applied thereto.

Fig. 2 is a fragmentary longitudinal sectional view of the window shown in Fig. 1 illustrating both the storm sash and lower sliding sash in closed position.

Fig. 3 is a view similar to Fig. 2 showing the sliding sash partly opened and the storm sash about to open.

Fig. 4 is a view similar to Fig. 3 showing the sliding sash partly open and the storm sash fully opened.

Fig. 5 is a view similar to Fig. 4 showing both the storm sash and sliding sash fully open.

Fig. 6 is a plan sectional view taken on line 6—6 of Fig. 2.

Fig. 7 is an elevational sectional view taken on line 7—7 of Fig. 2.

For the purpose of illustrating the application of my invention, I have shown in Fig. 1 a window indicated in its entirety at 10 which comprises a window frame 11 arranged with stops 12 and 13 to slidably support the usual upper and lower window sash 14 and 15. The sash 14 is formed with stiles 26, an upper rail, not shown, and a meeting rail 28, while the lower sash 15 is similarly constructed with stiles 29, a lower rail 30 and an upper rail 31. Both of these sash support window panes in the usual manner. In conjunction with frame 11 a storm window 16 is employed which is constructed with stiles 17 and 18 connected together through rails 19, 20 and 21 which also support window panes as customary. The storm sash 16 is hingedly connected to the header 22 of frame 11 through sash hangers 23 and 24 so as to permit of the swinging of the sash outwardly as shown in Fig. 1, or to permit the same to be swung into the rabbet adjacent the stop 13 formed in the frame 11 and indicated at 25.

My invention preferably employs two sash operators and fasteners, one attached to the stile 17 and the other attached to the stile 18 of the storm sash 16 and to the stops 12 and 13 of the frame. Both of these devices are identically constructed except that the one is left handed and the other right handed and for this reason only the sash operator and fastener attached to the stile 18 of the storm sash has been illustrated and will be described in detail in the specification. This sash operator is indicated in its entirety at 32.

The sash operator 32 consists of two arms 33 and 34 which are substantially equal in length and which are pivoted together through a rivet 35. These arms are pivoted at their free ends to the frame 11 of the window and to the stile 18 of the storm sash. When the sash is open the arms are extended as shown in Fig. 1 and when the sash is closed these arms come together as shown in Fig. 2 so that the said arms overlie one another. After the arms have become so positioned, said arms may be swung jointly from the position shown in Fig. 5 to that shown in Fig. 2. When disposed as shown in Fig. 2 the sash is held in place and locked to prevent opening of the sash from without.

For the purpose of attaching the arm 34 to the stile 18 of the storm sash 16, I employ a

bracket which is indicated in its entirety at 40. This bracket is preferably bent from a piece of sheet metal and is formed with a base 41 and with a flange 42 extending outwardly therefrom. 5 The base 41 may be secured to the stile 18 of the storm sash by means of wood screws 43 so that the flange 42 extends inwardly toward the sash 14 and 15. The extreme end of the arm 34 is pivotally connected to the flange 42 of bracket 40 through a rivet 44. By means of this construction the arm 34 is pivotally mounted upon the bracket 40 so that the same may be swung to occupy the various positions shown in Figs. 2, 3, 4 and 5.

15 The arm 33 is pivotally connected to the window frame 11 through a supporting plate 45. This supporting plate is preferably constructed of sheet metal and extends across the stop 13 and up to the stop 12. At the end of this plate 20 adjacent stop 12 the same is formed with a leg 27 which is seated against the frame 11 of the window 10. Plate 45 is attached to the frame through wood screws 47 and 48, the screw 47 being directly screwed into the frame proper 25 while the screw 48 is screwed into the stop 13. The supporting plate 45 is provided with a mounting plate 49 which is pivoted to the plate 45 through a rivet 50. The mounting plate is provided with a studded pin 51 (Fig. 6), which extends 30 through said plate and which is freely movable within an opening 68 in the plate 45. The head 69 of this stud is disposed between the plate 49 and the stop 13 and limits the movement of the plate 49 in a manner to be subsequently more fully described. The studded pin 51 is insertable into an opening 52 in the end of the arm 33 opposite pivot 35. By means 35 of this construction the arm 33 is pivotally mounted on the stud 51 and caused to swing about the same to open and close the storm sash.

For the purpose of swinging the arm 33 to open and close the storm sash 16, a lever 53 is employed which issues outwardly from said arm and which may, if desired, be constructed integral with reference thereto. The lever 53 is adapted to be swung from the position shown in Fig. 2 to that shown in Fig. 5. During the movement of said lever the storm sash 16 is caused to move from its closed position, as shown in Fig. 2, to its open position as shown in Fig. 5. In order to hold the arm 33 attached to the supporting plate 45 and to provide suitable friction between said arm and plate, a keeper 62 is employed which is best shown in Fig. 5. This keeper is constructed from a plate best shown in Fig. 7 which is formed at one end with a head 64 and at its other end with a foot 65. The head 64 is constructed with an opening 66 considerably larger in diameter than the diameter of the head of stud 51. In the application of the keeper 62 to the supporting plate 45 a screw 67 is employed which passes through the plate 45 and through said keeper and which is provided at its threaded end with a wing nut 70 by means of which the keeper may be frictionally forced against the lever 53. The foot 65 of keeper 62 serves as a fulcrum and when pressure is applied to said keeper intermediate its ends, through the nut 70 the head of said keeper is forced against the arm 33 urging the same against the mounting plate 49. The studded pin 51 is of such a length that the same projects outwardly beyond the arm 33 and is adapted to be received within the opening 66 in head

64 of said keeper. By means of this construction suitable friction is provided between the arm 33 and the supporting plate 45 through the agency of the mounting plate 49 whereby said arm may be retained in any desired position 5 so as to hold the sash 16 with any degree of opening.

For operating the sash swinging mechanism heretofore described a structure is employed which is best shown in Fig. 1. This structure 10 comprises a linkage indicated in its entirety at 71 which includes two links 72 and 73. The link 72 is pivoted to the protruding end of lever 53 through a rivet 74. Both of the links 72 and 73 are pivoted together through another rivet 75 15 while the link 73 is in turn pivoted to a mounting bracket 76 similar to the bracket 40. This bracket is constructed of sheet metal and is provided with a base 77 and a flange 78 extending outwardly therefrom. The link 73 is pivoted to 20 the flange 78 of said bracket through a pin 79 which is rigidly secured to said bracket and extends outwardly therefrom. This pin is adapted to freely enter an opening 80 in the link 73 whereby said link may be applied to or detached 25 from the bracket 76 by axial movement along said pin. Bracket 76 may be attached to the outer surface of the rail 30 of sash 15 through wood screws 81, best shown in Fig. 1.

The link 72 and the link 73 are formed with 30 stops 83 and 84 at the ends thereof through which the rivets 75 and 74 extend. These stops are formed by bending flanges from the metal from which said links are constructed which extend substantially parallel to the direction of the 35 length of the said links. The stop 84 is adapted to engage either of two abutments 85 and 86 on lever 53 and serve to limit the movement of said link and lever relative to one another. The stop 83 likewise is adapted to engage either of two 40 abutments 87 and 88 on the end of the link 72 opposite stop 84 by means of which the movement of said links relative to one another is controlled. It will be noted that the abutment causes the centers of the three pivots 69, 75 and 74 to 45 lie out of alignment so that the linkage will break when the sash is manipulated. The exact positions of these rivets when the same are closed is shown in Fig. 2.

For the purpose of assisting in applying the 50 hanger to the window three holes 56, 57 and 58 are employed which are drilled in the plate 45 and in the arms 33 and 34 respectively. When the various parts of the hanger are in proper position for mounting these three holes come 55 into register as shown in Fig. 2. A nail is then inserted through the said holes which hold the parts in proper position. Thereafter the sash operator is mounted upon the window frame and the bracket 40 is secured to the storm sash. The 60 distance from the window sill to the bottom of the bracket 76 is next measured and this bracket then attached to the rail 30 of sash 15 at the proper location. When the parts are arranged in accordance with the holes and so installed the 65 position of the studded pin 52 within the opening 68 is properly determined so that the said pin will have the necessary movement to permit of the proper functioning of the device.

In the opening of the storm sash the lower sash 70 is raised and the two arms 33 and 34 swing jointly from the position shown in Fig. 2 to that shown in Fig. 3 in which the two arms are still in substantial alignment. Before the storm sash can be opened it is necessary to arrest the movement 75

- of the arm 34 so as to cause the swinging of the sash instead of the further joint movement of the arms. This is accomplished by means of a stop 89 which is formed on the arm 34 and which 5 is adapted to engage the base 41 of bracket 40. When the lever 53 is swung, arm 34 is moved toward the sash until said stop engages bracket 40. Further movement of lever 53 causes the storm sash 16 to be swung outwardly about the storm sash hangers 23 and 24 as pivots. As soon 10 as the storm sash leaves the rabbet 25 the arm 34 starts swinging away from said sash until the arms 33 and 34 are in the positions shown in Fig. 4 in which the storm sash is fully opened. 15 When the parts are disposed as shown in Fig. 4 the two jointed links 72 and 73 are substantially at right angles to one another, the link 72 extending horizontally. In such position the sash 15 is only partly open. If now the sash 15 20 be further opened the two links 72 and 73 jack knife and finally come into alignment as shown in Fig. 5. In this position both the storm sash and the sliding sash are fully open. Where the storm sash and sliding sash occupy the positions 25 shown in Fig. 4, the opening afforded through the storm sash is much greater than through the sliding sash. Such is the case with the form of my invention shown in my copending application for patent above referred to. By means of the 30 jointed link construction the sliding sash can be opened a greater distance than is possible with my previous invention so as to afford an opening more nearly equal to that through the storm sash.
- To prevent the links 72 and 73 from striking the sash 15, a lug 90 is formed on the link 73 which engages the base 77 of bracket 76 in much the same manner as the lug 89 engages the base 41 of bracket 40. This lug is so designed that 35 the links 72 and 73 clear the sash 15 and are held in proper position to cause the movement of the sash operating mechanism. In order that the two links break when the sash is traveling upwardly the abutment 88 and stop 83 are employed. To cause the links to break in the proper direction when the sash is traveling downwardly the abutment 87 and stop 83 are employed and also the abutment 85 and stop 84. Stop 84 and abutment 85 come into action shortly after 40 the sash has passed the position shown in Fig. 4. Stop 83 and abutment 87 come into action on downward movement of the sash at some position between the positions shown in Figs. 5 and 4. The use of the invention is exceedingly simple. 45 When it is desired to open both sashes the sliding sash is raised until the stop 89 reaches the bracket 40. The storm sash then commences to open. The degree of opening of both the sashes can be controlled by further raising of the sliding sash. If the storm sash is fully open the sliding sash can be still further opened as previously 50 described. To close the sash it is merely necessary to move the sliding sash into closing position which automatically brings about closing of the storm sash.
- My invention is highly advantageous in that the sash operator may be utilized to give a much greater degree of opening of the sliding sash than is possible where the operator such as shown in 55 my copending application for patent is employed. After the storm sash has been fully opened the sliding sash may be moved an appreciable amount without changing the position of the storm sash. The device is readily applied to and removed 60 from the window frame and sliding sash and when once applied readily remains in proper position. With the form of the invention disclosed in this application the leverage for opening the storm sash is more advantageously applied so that less force is required in raising the sliding sash than would otherwise be necessary, thus making it possible to loosen the storm sash in the event the same sticks through the action of ice or snow. My invention may be attached 65 to either an upper or lower sash, as desired. When the sliding sash is closed the storm sash is locked so that intrusion from the exterior is effectively prevented.
- Changes in the specific form of my invention, as herein disclosed, may be made within the 15 scope of what is claimed without departing from the spirit of my invention.
- Having described my invention, what I claim as new and desire to protect by Letters Patent is:
1. A sash operator comprising a pair of jointed arms for attachment to the frame and a sash of a window, a lever connected to one of said arms for swinging the same, and a pair of jointed links connected to the lever for operating said lever. 20
  2. In combination with a window having a frame, a sash pivoted thereto and another sash movable relative to the frame, sash operating means for swinging said pivoted sash, and a pair of jointed links for operating said sash operating means, one of said links being moved by said 25 second named sash.
  3. In combination with a window having a frame, a sash pivoted thereto and another sash 30 slidable along said frame, sash operating means for swinging said pivoted sash, a pair of jointed links for operating said sash operating means, and means for pivoting one of said links to said sliding sash.
  4. In combination with a window having a frame, a sash pivoted thereto and another sash 35 movable relative to the frame, sash operating means for swinging said pivoted sash, and a pair of members for operating said sash operating means, said members being movable relative to one another and being moved by said second 40 named sash, said members idling throughout a portion of the movement thereof and operating said sash operating means throughout another portion of the movement thereof.
  5. In combination with a window having a 45 frame, a sash pivoted thereto and another sash slidable along said frame, a pair of jointed arms, means for pivoting one of said arms to the swinging sash, means for pivoting the other of said arms to the frame, a lever for swinging one of said arms to cause movement of the swinging sash, a pair of jointed links, means for connecting one of said links to the lever and means for connecting the other of said links to the sliding sash, said links being arranged so that the same 50 function to open the swinging sash throughout the initial movement of the sliding sash.
  6. In combination with a window having a 55 frame, a sash pivoted thereto and another sash slidable along said frame, a pair of jointed arms, means for pivoting one of said arms to the swinging sash, means for pivoting the other of said arms to the frame, a lever for swinging one of said arms to cause movement of the swinging sash, a pair of jointed links, means for pivoting one of 60 said links to the lever, means for pivoting the other of said links to the sliding sash, and a stop for limiting the movement of said links to hold the centers of said pivots and joint out of alignment when said links are in extended position.

7. In combination with a window having a frame, a sash pivoted thereto and another sash slideable along said frame, a pair of jointed arms, means for pivoting one of said arms to the frame, 5 a lever for swinging one of said arms to cause movement of the swinging sash, a pair of jointed links, means for pivoting one of said links to the lever, means for pivoting the other of said links to the sliding sash, and a stop on each of said 10 links for limiting the movement of said links and lever to hold the centers of the joint of the links, the pivot of the one link to the other and the pivot of the other link to the sash out of alignment when said links are in extended position.
15. 8. In combination with a window having a frame, a sash pivoted thereto and another sash slideable along said frame, a pair of jointed arms, means for pivoting one of said arms to the swinging sash, means for pivoting the other of said 20 arms to the frame, a lever for swinging one of said arms to cause movement of the swinging sash, a pair of jointed links, means for pivoting one of said links to the lever, means for pivoting the other of said links to the sliding sash, and 25 means acting between the sliding sash and the link pivoted thereto for limiting the movement of said link relative to the sash.
9. In combination with a window having a frame, a sash pivoted thereto and another sash 30 slideable along said frame and up to one of the ends of the frame, a pair of jointed arms, means for pivoting one of said arms to the swinging sash intermediate its ends, means for pivoting the other of said arms to the frame, a lever connected 35 to one of said arms, a pair of jointed links, means for connecting one of said links to said lever and means for connecting the other of said links to the sliding sash at a locality closer to the aforementioned end of the frame than the pivot of said 40 arm to the swinging sash.
10. In combination with a window having a frame, a sash pivoted thereto and another sash slideable along said frame and up to the sill thereof, a pair of jointed arms, means for pivoting 45 one of said arms to the swinging sash intermediate its ends, means for pivoting the other of said arms to the frame, a lever connected to one of the arms, a pair of jointed links, means for connecting one of said links to said lever and means for connecting the other of said links to the sliding sash at a locality closer to the sill 50 than the pivot of said arm on the swinging sash.
11. In combination with a window having a frame, a sash pivoted thereto and another sash 55 movable relative to the frame, sash operating means for swinging said pivoted sash, said sash operating means including a member movable toward and from the second named window and actuating means for causing movement of said sash operating means, said actuating means being connected to said second named sash and engaging said member, said actuating means operating to move said operating means when the member 60 is in proximity to said second named window and ceasing to operate said sash operating means when said member is in a position away from said second named sash.
12. In combination with a window having a frame, a sash pivoted thereto and another sash 65 slideable along said frame and up to one of the ends of the frame, a pair of jointed arms, means for pivoting one of said arms to the swinging sash, a plate for pivoting the other arm relative 70 to said frame, said lever, plate and last named arm having registering holes through which a key may be inserted to hold the parts in proper position for attachment to the window and means for operating said lever to cause movement of the swinging sash when the key is removed. 75
13. A sash operator for use with a window having a frame, a sash pivoted thereto and another sash movable relative to the frame, sash operating means for swinging said pivoted sash including a movable member, a link connected to the movable sash, a second link connected to the movable member and connecting means for connecting said links together, said connecting means 10 guiding said links for movement relative to one another. 15
14. In communication with a window having a frame, a sash pivoted thereto and another sash movable relative to the frame, sash operating means for swinging said pivoted sash, a pair of jointed links for operating said sash operating means, one of said links being moved by said second named sash, and means for holding said links from collapsing when the sash are in closed position to cause movement of the swinging sash 20 through pushing movement of said links. 25
15. A sash operator for use with a window having a frame, a sash pivoted thereto and another sash movable relative to the frame, sash operating means for swinging said pivoted sash including a swinging member extending transversely of the frame when the sashes are closed, a link pivoted at one end to said member and depending therefrom, a second link pivoted to said first link at its other end and depending therefrom, and means 30 for pivoting said second link to said movable sash. 35
16. A sash operator for use with a window having a frame, a sash pivoted thereto and another sash movable relative to the frame, sash operating means for swinging said pivoted sash including a movable member, means for supporting said member for swinging movement relative to the frame, said member extending across the frame when the sash are closed and extending outwardly 40 from the frame when the sash are open, a link pivoted to said movable member and depending therefrom when the sash are closed and extending across said frame when the sash are partly 45 opened and a second link pivoted to said first link and to said movable sash, said second link depending from the first link in both of said 50 positions of said first link. 55
17. A sash operator for use with a window having a frame, a sash pivoted thereto and another sash movable relative to the frame, sash operating means for swinging said pivoted sash including a movable member, means for supporting said member for swinging movement relative to the frame, said member extending across the frame when the sash are closed and extending outwardly 60 from the frame when the sash are open, a link pivoted to said movable member and depending therefrom when the sash are closed and extending across said frame when the sash are partly 65 opened and a second link pivoted to said first link and to said movable sash, said second link depending from the first link in both of said 70 positions of said first link, said first link being of a length less than the distance between the outermost position of the axis of the pivot between said movable member and first link and the movable sash. 75

CHESTER O. GOSERUD.
